SUCTION CLEANER

Harry B. White, North Canton, Ohio, assignor to
 The Hoover Company, North Canton, Ohio, a
 corporation of Ohio

Application May 9, 1938, Serial No. 206,761

6 Claims. (Cl. 15—8)

The present invention relates to suction cleaners in general and particularly to power-transmission means in suction cleaners. More specifically the invention comprises a suction cleaner in which the surface covering agitator can be completely disconnected from the driving motor.

It is an object of the invention to provide a new and improved suction cleaner. It is another object of the invention to provide a new and improved power-transmission means in a suction cleaner. A further object of the invention is to provide a suction cleaner in which the driving motor can be disconnected from the surface covering agitator. A still further object is to provide a suction cleaner in which the surface covering agitator is connectable to or disconnectable from the driving motor by means which do not include a running idler pulley. Still another object of the invention is to provide means by which the motor-driven driving pulley which is connected to the cleaner agitator by a belt is shifted entirely from connection with the motor to permit the agitator to remain inoperative. Still another object of the invention is to provide a suction cleaner in which the motor driven agitator pulley is shiftable from its driving connection with the motor to a stationary position in which it is entirely free from the motor. Another object of the invention is to provide a suction cleaner in which the drive pulley is completely disconnected from the driving shaft by manually operable means for the purpose of disconnecting the agitator from the driving motor. These and other more specific objects will appear upon reading the following specification and claims.

Referring now to the drawings in which preferred embodiments of the present invention are disclosed:

Figure 1 is a bottom view of a suction cleaner with parts of the casing broken away to show the clutch mechanism constructed in accordance with the present invention;

Figure 2 is a longitudinal section through the cleaner shown in Figure 1 upon the line 2—2 thereof;

Figure 3 is an enlarged showing of the section of the clutch mechanism found in Figure 1;

Figure 4 is a view similar to Figure 3 but with the clutch in the disconnected or open position;

Figure 5 is a view looking in the direction of the arrows upon the line 5—5 of Figure 4 and shows the clutch-operating lever in the clutch-open position;

Figure 6 is a detail view of the centrifugal weight unit of the clutch;

Figure 7 is a side view of the unit shown in Figure 6;

Figure 8 is a view, partly in section, of the pulley unit;

Figure 9 is a view of the clutch mechanism in the driving relationship being a section taken upon the line 9—9 of Figure 2.

The modern suction cleaner accomplishes its cleaning purpose by combining surface agitation with air cleaning. Both functions are essential to remove all of the foreign material from a surface covering to be cleaned. The modern suction cleaner, however, is also adapted for off-the-floor cleaning as well as on-the-floor cleaning. In the former operation, the surface-agitating means perform no useful function and it is desirable that they be rendered inoperative. To effect this disconnection of the agitating means the present invention provides an improved construction, a construction in which there are no friction losses with the agitator disconnected from its driving source, and in which the connecting means are sure and positive in their operation.

The cleaner in which the invention is embodied includes an ambulatory nozzle unit which pivotally carries a motor-fan-handle-bag unit, which is commonly referred to as the motor-fan unit. The nozzle unit is seen to comprise a nozzle 1 provided with front and rear surface-contacting lips 2 and 3 respectively, which define the nozzle mouth. Passageways 4 and 5 open into the nozzle and extend rearwardly and upwardly therefrom, the passageway 4 serving as an air passageway and the passageway 5 functioning as a belt channel. Side walls 6, 6 extend backwardly from the nozzle proper 1, and at the sides of the passageways 4 and 5, to form rearward extensions of the nozzle unit in order that it can support the pivoted parts of the machine in all angular positions. Beneath the walls 6, 6 and immediately in the rear of the nozzle 1 are front supporting wheels 7, 7 while at the rear of the side arms, formed by the walls, are rear supporting wheels 8, 8. The latter are pivotally carried by U-frame 9 which is itself pivotally mounted upon transverse shaft 10 connecting the nozzle unit arms. The shaft 11 of the wheels 8, 8 is L-shaped and extends upwardly through one of the walls 6 to be provided at its top with suitable rotatable knob 12 by which it can be raised and lowered for the purpose of raising and lowering the wheels.

The motor-fan unit is pivotally mounted for limited angular rotation upon the nozzle unit and more particularly between the rearwardly extending side walls 6, 6. Suitable sealed joints, as illustrated at 15 pivotally mount the casing of motor-fan unit 16 upon the nozzle unit, and more particularly upon and between the inner walls of passageways 4 and 5. The casing of the unit 16 is in fact a motor casing adjacent the passageway 5 and a fan casing adjacent the air passageway 4. Within the latter portion is positioned a suction-creating fan 17 which is carried by the extended motor shaft 18 which also extends into the passageway 5 being suitably mounted in bearings, as at 19. The fan chamber is connected to the air passageway 4 at its eye 20 and is formed with an exhaust outlet 21 which is flanged at its end and carries manually operable clamping nuts 22, 22 by which the ring 23 of a dust bag 24 may be removably clamped. The exhaust outlet 21 extends between the rearwardly extending side walls 6, 6 of the nozzle unit, as is clearly seen in Figures 1 and 2, the arrangement being such that the motor-fan unit can pivot from a position in which the exhaust outlet extends substantially horizontally, as illustrated in Figure 2, to a position in which it extends substantially vertically having rotated through an angle of 90 degrees or thereabouts.

An operating handle 27, through which current-carrying leads 28, 28 extend, seats in a socket 29 formed on the motor-fan unit casing immediately above the exhaust outlet 21. The handle may be of any suitable design and preferably supports the upper end of the dust bag 24 in a manner common and well known in the suction cleaner art. It is through the handle 27 that the operator exerts the propelling force upon the cleaner and angular movement of the handle is permitted by the rotation of the motor-fan unit 16 upon the nozzle unit. The handle is retained within various positions, and certain intermediate ranges of movement, by handle-position-controlling means comprising an arcuate sector 32 formed upon its periphery with detent seats with which cooperates a spring-pressed roller detent 33 pivotally carried by the wheel supporting shaft 10 but spring-pressed into contact with the sector by a coil spring 34.

The cleaner proper is completed by the rotary agitator 38 formed with surface agitating elements 39 and a pulley 40 which is positioned within the nozzle 1 and is adapted to contact a surface covering undergoing cleaning between the lips 2 and 3. A power-transmission belt 41 extends rearwardly from the agitator pulley 40 through the belt channel 5 to the driving pulley 42 which is driven by the motor shaft 18 through a clutch mechanism which comprises the present invention.

According to the present embodiment of the invention the motor shaft 18 is continued or extended at its belt housing end by an extension 45 which is suitably screw threaded to the shaft proper 18. Extension 45 carries a radial plate member 46 to the outer face of which is riveted a friction disc 47 having a beveled periphery, as is clearly illustrated in Figure 6. Centrifugal weights 49, 49 are pivoted upon pins carried by plate 46 and extend upon both sides thereof. Circular springs 50, 50 extend between the weights 49, 49 and exert a force which at all times urges radially outwardly the side of the weights having the greater mass so that the opposite ends thereof, which are formed as fingers,

are held in an inner position. The extension 45, the plate 46 with its friction disc 47, and the centrifugal weights 49, 49 rotate at all times with the motor shaft 18 and form what may be called the shaft or driving unit of the clutch.

The pulley unit 42 is seen to comprise, in addition to the pulley surface proper, an enlarged drum 54 formed with one beveled side and with a peripheral flange 55. A counterbored sleeve 10, 56 forms a part of the unit and extends inwardly thereof being provided upon its inner end with a beveled shoulder 57. Unit 42 is adapted to slide axially upon the reduced end of shaft extension 45 and in its inner position, as illustrated in 15 Figure 3, the sleeve 56 is in contact with, and is retained in place by the action of the centrifugal fingers 49, 49. The relationship of the bevels upon the shoulder 57 and at the ends of the fingers 49, 49 is such that a sufficient axial force 20 exerted upon the pulley forces the fingers outwardly to disengage them from the shoulder 57 and permits the pulley unit to slide axially outward on the shaft. With the pulley in the inner and driving relationship however, the friction disc 47 of the driving unit is in contact with and 25 seats the beveled surface of the drum 54, as illustrated in Figure 3, and rotation of the shaft causes rotation of the pulley unit. In the outer axial position of the pulley unit, however, the drum is moved from the friction disc, as illustrated in Figure 4 and the entire pulley unit, including the sleeve 56, is supported free from the driving unit by means of a stationary seat. This stationary seat comprises an enclosing ring 30 35 60 of fiber material carried by a supporting bracket 61, the ring or seat 60 being so positioned that as the pulley unit slides axially outward from its inner position a cylindrical portion of the drum 54 slides into the seat to the position 40 illustrated in Figure 4. Thereafter the entire pulley unit is supported free from the driving shaft and the driving unit of the driving shaft.

According to this embodiment of the invention the pulley is disconnected from the driving motor as the cleaner handle is moved to the vertical position. This is known as the storage position of the handle and is the position which it assumes normally when the machine is used in off-the-floor cleaning. To accomplish this 45 result there is provided upon the side of the casing of fan-motor unit 16 a cam boss 65 which contacts and pivots outwardly, as the handle is pivoted into the vertical position, a lever 66 carried by shaft 67. U-shaped arms 68, 68 form a frame which is fixedly secured by pins to the shaft 67 so that the buttons 69, 69 which are spaced upon the opposite sides of each arm immediately adjacent the peripheral rim 55 of the pulley drum 54, are movable into contact with the rim to shift the pulley unit axially as the 50 shaft is rotated by the lever. The pulley unit is shifted by the shifting means into the seat 60 where it is held so long as the handle is in the vertical position. Upon the movement of boss 65 from contact with the lever 66, however, a coil spring 70 encircling and acting upon the shaft 67 moves the arms 68, 68 and so the buttons 69, 69 upon the opposite side of the drum flange 55, into contact therewith and the pulley unit is shifted from its stationary seat 60 axially of the driving shaft and into contact with the driving unit, as aforescribed.

The operation of this embodiment of the invention is as follows. In on-the-floor cleaning the rotation of the suction-creating fan 17 under 75

the impetus provided by the driving motor of the machine creates a reduced pressure within the nozzle 1 which draws cleaning air thereinto between the lips 2 and 3. The surface covering undergoing cleaning is lifted into contact with the rotating agitator 38 which is driven by means of the power transmitting belt 41 the pulley 42 being in this relationship positively driven by the motor shaft. The foreign material dislodged from the surface covering is carried by the air stream through the passageway 4 into the fan chamber and exhausted by the suction-creating fan 17 through the exhaust outlet 21 into the filter bag 24 at which point the suspended foreign material is removed from the air which passes out into the surrounding atmosphere. So long as the machine continues to function as an on-the-floor cleaner the relationship described continues and the agitator is directly connected to the power source and rotates at all times.

If the operator desires to convert the cleaner into an off-the-floor cleaner, he raises the operating handle 27 to the vertical position and suitably connects to the eye 20 of the fan chamber, in any usual manner which forms no part of the present invention, the dusting tools so that articles, etc., positioned off the floor may be cleaned. The movement of the handle to the vertical position functions to disconnect entirely from the driving motor the agitator 38 by axially shifting the pulley unit 42 onto the stationary seat 60 in which it is spaced from all rotating parts actuated by the motor. This operation results from the movement of the casing-carried boss 65 into contact with the operating lever 66 which in turn rotates the shaft 67 carrying the actuating mechanism comprising the arms 68, 68. The movement of these arms brought the buttons 69, 69 upon one side of the peripheral flange 55 into contact therewith and the continued movement of the arms caused the pulley unit to be shifted axially, it being necessary only to exert a slight axial force to cause the sloping shoulders of the beveled shoulder 57 of pulley carried sleeve 56 to pivot the locking centrifugal fingers 49 outwardly. A further slight axial movement of the pulley unit seats the hub portion of the unit within the seat 60 where it is retained by the arms 68, 68 so long as the boss 65 remains in contact with the actuating lever 66 which is, of course, dependent upon the angular position of handle 27.

When the operator desires again to return the machine to its on-the-floor cleaning relationship the handle 27 is pivoted downwardly from the vertical position and the cammed boss 65 moves out from its contact with the actuating lever 66. The lever-actuated arms 68, 68 then move in the opposite direction under the actuation of the coil spring 70 and the pulley unit is shifted inwardly from its stationary seat 60. The inward radial movement of the pulley unit 42 first brings the beveled shoulder 57 of the sleeve 56 into contact with the inner ends of fingers 49, 49 and these fingers are cammed outwardly until they ride over the top of the shoulder and lock upon the opposite side thereof, as illustrated in Figure 3. The springs 50, 50 acting upon the fingers 49, 49 together with the centrifugal force exerted by the fingers upon the opposite side of their pivot points from the shoulders, the greater mass of the fingers being at that point, serves to secure the sleeve 56, and so the pulley unit 42, in fixed position relative to the driving unit 45 of the motor shaft. In this fixed

position the beveled face of the drum 54 of the pulley unit seats in contact with the fiber plate 47 and driving contact is positive between the drive shaft and the unit and the pulley.

5 I claim:

1. In a suction cleaner or the like, a shaft, a friction pulley seat carried by said shaft, a pulley including a pulley surface and a drum slideable on said shaft and adapted to seat with said drum on said seat in one axial position, centrifugally operable fingers to clamp said pulley in seating relationship to said seat, spring means to hold said fingers in clamping relationship in the absence of centrifugal force, a stationary pulley seat to receive and support said pulley free from said shaft in a second axial position, said stationary seat contacting the drum of said pulley, and manually operable means to contact said pulley drum to move said pulley between said seats.

2. In a suction cleaner or the like, a shaft, a pulley seat carried by said shaft, a pulley slideable on said shaft and including a drum adapted to seat on said seat, a centrifugally actuated spring-pressed retainer securing said pulley to said seat, a stationary pulley seat adapted to receive said pulley upon the latter being moved axially from the shaft-carried seat, and manually operable means normally out of contact with

30 said pulley to shift said pulley between said seats.

3. In a suction cleaner or the like, a stationary body, a rotatable shaft carried by said body, a pulley seat carried by said shaft and rotatable therewith, a stationary pulley seat carried by said body spaced axially of said shaft from said rotatable pulley seat, a pulley including surfaces to seat singly and independently upon said seats in spaced axial positions of said pulley, said pulley being completely detached from said shaft in one position and from said stationary body in the other position, centrifugally operated means carried by said shaft to secure said pulley to said rotatable seat, and manually operable means spaced entirely from said pulley when on said 45 rotatable seat to shift said pulley between said seats.

4. In a suction cleaner or the like, a stationary body, a rotatable shaft carried by said body, a pulley seat carried by said shaft and rotatable therewith, a stationary pulley seat carried by said body spaced axially of said shaft from said rotatable pulley seat, a pulley including surfaces to seat singly and independently upon said seats in spaced axial positions of said pulley, said pulley being completely detached from said shaft in one position and from said stationary body in the other position, a plurality of centrifugally operated latching members carried by said shaft, spaced circumferentially therearound, to secure said pulley to said rotatable seat, spring means exerting a latching force on said latching members sufficient to prevent unintentional displacement of said pulley from said seat in the absence of centrifugal force, and manually operable means carried by said stationary body to shift said pulley between said seats.

5. In a suction cleaner or the like, a stationary body, a rotatable shaft carried by said body, a rotatable pulley seat comprising a beveled friction plate carried by said shaft and rotatable therewith, a stationary pulley seat of non-metallic material carried by said body spaced axially of said shaft from said rotatable pulley seat, a pulley including surfaces, one of which is beveled, to seat singly and independently upon said

seats in spaced axial positions of said pulley, said pulley being completely detached from said shaft in one position and from said stationary body in the other position, centrifugally operated means carried by said shaft to secure said pulley to said rotatable seat, and manually operable means pivotally mounted on said stationary body to shift said pulley between said seats.

6. In a suction cleaner of the type having an ambulatory nozzle unit including a nozzle and supporting means, a rotary agitator in said nozzle, and a pivoted fan chamber unit mounted on said unit including a fan chamber and a han-

10 dle, a driving shaft actuating said fan, and power-transmission means between said agitator and said shaft; a rotatable pulley seat carried by said shaft, a stationary pulley seat carried by said nozzle unit, in axial alignment with respect to said shaft, and spaced axially from said rotatable seat, a pulley unit shiftable axially between said pulley seats, centrifugally operated means carried by said shaft to secure said shaft to said rotatable seat, and means actuated by the pivotal movement of said fan chamber unit to shift said pulley unit between said seats.

HARRY B. WHITE.
